UNITED STATES PATENT OFFICE.

STEPHEN SZABO, OF PHILADELPHIA, PENNSYLVANIA.

PUZZLE.

1,263,960.

Specification of Letters Patent. Patented Apr. 23, 1918.

Application filed October 20, 1917. Serial No. 197,692.

To all whom it may concern:

Be it known that I, STEPHEN SZABO, a citizen of Hungary, residing at Philadelphia, in the county of Philadelphia and State of Pennsylvania, have invented new and useful Improvement in Puzzles, of which the following is a specification.

This invention relates to puzzles of that class in which a form of predetermined size and configuration is divided into parts, the object of the puzzle being to assemble the divided parts so as to remake the form from which the same are divided.

The puzzle made in accordance with my invention preferably comprises a member made in the shape of a cross. I divide this cross into a number of substantially Z-shaped members and a series of elongated L-shaped members.

20 In the drawing:

Figure 1 is a perspective view showing the parts assembled.

Fig. 2 is a plan of the same showing the parts separated.

25 Referring to the drawing it will be seen that the assembled parts form a member in the shape of a cross. The parts may be formed of any suitable material such as cardboard, metal and the like. The cross is 30 composed of three members, indicated by the reference numeral 1 of substantially Z-shape, that is, composed of a straight part having each end bent at right angles and in oppo-

site directions. It will be seen that the four long sides of the member are of equal length. 35 The cross also consists of a pair of members 2 of substantially L-shape, though the vertical member 3 is of much greater length than the horizontal member 4. It will be seen that the member 4 is of the same dimension as the end portions of the member 1. The two members 2 are placed together with part 4 of one member engaging the end of the part 3 of the other member, thus forming the lower part of the cross, this part being 45 of twice the thickness of the parts 3. The members 1 are then placed together with one of the members in vertical position and the other two in horizontal position as clearly shown in Fig. 1, and then the said members are placed in engagement with the members 2. It will thus be seen that a figure in the 50 shape of a cross is formed.

What I claim is:

1. A puzzle comprising a pair of members of substantially L-shape, and three members of substantially Z-shape placed together to form a cross. 55

2. A puzzle comprising a pair of members of substantially L-shape, one part of the L being of much greater length than the other part, and three members of substantially Z-shape of less length than the L-shaped members, placed together to form a cross. 60

In testimony whereof I affix my signature. 65
STEPHEN SZABO.
